UNITED STATES PATENT OFFICE

150,067

DESIGN FOR A COMBINATION GARDEN TOOL

Clyde H. Fleming, Fort Worth, Tex.

Application October 18, 1946, Serial No. 134,023

Term of patent 3½ years

(Cl. D35—2)

To all whom it may concern:

Be it known that I, Clyde H. Fleming, a citizen of the United States, residing at Forth Worth, in the county of Tarrant and State of Texas, have invented a new, original, and ornamental Design for a Combination Garden Tool, of which the following is a specification, reference being had to the accompanying drawing, forming a part thereof.

Figure 1 is a plan view of a combination garden tool, showing my new design.

Figure 2 is an elevational view of the tool shown in Figure 1.

I claim:

The ornamental design for a combination garden tool, substantially as shown,

CLYDE H. FLEMING.
